UNITED STATES PATENT OFFICE.

SEBASTIAN G. BRINKMAN, OF FORDS, NEW JERSEY.

CARBURETER.

1,243,250.

Specification of Letters Patent. Patented Oct. 16, 1917.

Application filed March 23, 1916. Serial No. 36,065.

To all whom it may concern:

Be it known that I, SEBASTIAN G. BRINKMAN, a citizen of the United States, and a resident of Fords, in the county of Middlesex and State of New Jersey, have invented certain new and useful Improvements in Carbureters, of which the following is a specification.

This invention relates to a carbureter of novel construction, in which the vacuum or suction induced by the engine for drawing up the air will induce a second vacuum or suction at the mouth of the oil nozzle. This second vacuum is of such intensity that it will lift the oil to a great height, so that the same may be drawn directly from the tank, and that consequently the intervening oil cup and float valve mechanism heretofore generally employed, may be dispensed with. The invention also relates to various other features of construction all as more fully pointed out in the specification and appended claims.

In the accompanying drawing:

Fig. 1 is a vertical longitudinal section of a carbureter embodying my invention;

Fig. 2 is a horizontal section on line 2—2 of Fig. 1;

Fig. 3 a longitudinal section through the oil nozzle, and

Fig. 4 a diagram showing the carbureter installed in a motor vehicle.

Upon the upright shell or casing 1 of the carbureter is mounted a flanged collar 2 leading to the manifold and furnished with a throttle valve 3 as usual. Into the lower end of shell 1, there extends an oil pipe 4 that is centered within the shell, by means of a plurality of radially disposed tubular ducts or branches 5. These branches are inclined upwardly from the pipe toward the shell, and open into the inner upwardly inclined wall 6 of an oil chamber 7 the outer wall of which is formed by the correspondingly inclined lowermost section 8 of shell 1. Pipe 4 passes through the apertured elbow 9 of an air ingress pipe 10, having a suitable valve 11; the lower threaded end of pipe 4 carrying a nut 12, by means of which the air pipe is secured to pipe 4 and consequently to the shell. It will be seen that by the construction described, the air entering through pipe 10 is free to be drawn upwardly between ducts 5 into the lower tapering portion of shell 1 which is encom-

passed by oil chamber 7, and thence into the upper portion of the shell, such upper portion being formed of an outwardly flaring section 13, so that the shell is here Venturi-shaped. At the top of outwardly flaring section 13, the shell is further provided with an inwardly inclined section 14.

The oil chamber 7 which is very narrow in cross section, inclines inwardly from bottom to top, and is furnished at its upper end with an inwardly opening circular or continuous annular nozzle 15. This nozzle is formed by pronounced inward bends or deflections 16, 17 of the walls 6, 8 of chamber 7, directly beneath the lower end of section 13, so that in this way, the nozzle is arranged transversely to the axis of the carbureter, and consequently discharges the oil at the neck formed between the sections 8 and 13, at or at about right angles to the flow of air. By making the nozzle of annular form, there is obtained, a continuous discharge slit of maximum length so that the fuel will be sucked from the entire circle of the nozzle by the air current flowing through the neck of the Venturi-shaped shell, thus preventing the formation of inert spaces at the nozzle.

In alignment with pipe 4, there extends into the upper portion of shell 1, a tubular support 20 having a stepped bore, and adapted for the correspondingly stepped spindle 21 of a tapering needle valve 22. This valve depends into oil tube 4 and passes through a port 23 formed within the upper part of a bushing 24, encompassed by said tube and connected at its lower end by a coupling 25 to the oil tube 19. Bushing 24 is vertically adjustable, its lower threaded end being engaged by a hand nut 26 which is held against vertical displacement by a flange 27 of nut 26 that enters a peripheral groove of nut 26. Thus by turning the latter, bushing 24, may be raised or lowered to correspondingly reduce or increase the clearance of port 23, a packing 28 serving to keep the parts tight. The clearance of port 23 is considerably less than the area of nozzle 15, so that the suction created at the nozzle will induce a suction of considerably increased intensity at the port.

The upper end of the spindle 21 protrudes from tube 20, and carries a pear shaped or bulged weight or governor 29 which has an axial bore to accommodate tube 20 on which it is slidable. This governor will rise or fall

with an increase or decrease of the engine-speed, and will thus control the size of the annular air passage formed between its belly and the neck of the shell 1 into which nozzle 15 opens. With all positions of the governor however, this air passage will always remain the narrowest free space within the body of the shell, so that the air will obtain its maximum pressure and velocity during its flow across the annular nozzle 15. By the rise and fall of the governor, the richness of the mixture is increased with the speed of the engine in the manner required. In order to prevent an abrupt up and down movement of the governor, spindle 21 is provided with an outwardly extending rib 30 engaging a spiral groove 31 of steep pitch formed on the inner face of tube 20. Thus as the governor rises or falls it will turn on its axis, so that the speed of its movement is checked by the play of the rib 30 within groove 31.

The correlation of the parts is such that even at the lowest position of the governor, 25 there is still a narrow air port formed, opposite nozzle 15, so that an air current will be free to flow around the governor at the minimum speed of the engine.

In operation, the suction of the engine, 30 will induce an upward flow of air within the shell, which, as has already been stated, obtains its maximum force at the neck of the shell. In this way, a vacuum will be formed at the nozzle, which has a strong suctional effect on the fuel. This suctional effect being greatly intensified at the fuel-controlling port (owing to the difference in clearance) produces such a forceful lifting effect that the fuel may be raised into the carbureter through a considerable height or distance. The air and fuel will commingle at the nozzle, and will then be thoroughly intermixed in the gradually widening section 13, so as to form a homogeneous mixture, 45 which mixture will by the contracted section 14, be delivered to the manifold. Inasmuch as by my invention, the fuel may be drawn by the suction of the engine directly into the carbureter with great force, I am enabled to entirely do away with the oil cup heretofore generally employed, thus greatly simplifying and cheapening the construction, and doing away with the various objections inherent in oil cups. As illustrated diagrammatically in Fig. 4, the fuel is drawn from a lower level fuel tank 18, by a comparatively long pipe 19 directly, or without the interposition of an oil cup, into the lower end of the carbureter shell.

60 I claim:

1. A carbureter comprising a Venturi-shaped shell, having a contracted neck, a

fuel chamber having an inwardly directed annular nozzle at said neck, said nozzle extending at substantially right angles to the 65 axis of the shell, and a bulged governor movable within the shell across said nozzle and forming a restricted air passage therebetween, said governor controlling the width of said passage. 70

2. A carbureter comprising a Venturi-shaped shell having a contracted neck, a fuel chamber having an inwardly directed nozzle at said neck, said nozzle extending at substantially right angles to the axis of the 75 shell, a bulged governor movable within the shell across said nozzle and forming a restricted air passage therebetween, and a fuel inlet port for the fuel chamber, the clearance of said port being considerably less 80 than the area of the nozzle, whereby the suction produced by the air at the nozzle is intensified at said port.

3. A carbureter comprising a Venturi-shaped shell having a contracted neck, a fuel chamber having an inwardly directed annular nozzle extending at substantially right angles to the axis of the shell, a bulged governor movable within the shell across said nozzle and forming a restricted air passage 85 therebetween, a fuel inlet port for the fuel chamber, the clearance of said port being considerably less than the area of the nozzle, and a fuel tank communicating directly 90 with the shell. 95

4. A carbureter comprising an upright shell having an inwardly inclined lower section, an outwardly inclined upper section, a contracted neck formed between said sections, an oil chamber extending along the lower inwardly inclined section, said oil chamber having a nozzle that opens into the shell at said neck at substantially right angles to the axis of the shell, an oil tube extending axially through the shell and connected to said chamber, a valve seat adjustable within said tube, a governor mounted on said tube and slidably within the neck, said governor forming an upright air passage across the nozzle, and a needle valve 100 mounted within the tube and engaging said valve seat. 105

5. A carbureter comprising a shell, an oil pipe, an oil chamber extending along the wall of the shell and having an inwardly 115 deflected annular nozzle, means for connecting the oil pipe with the oil chamber, a tubular support within the shell, a needle valve that projects into the oil pipe and has a spindle mounted in the tubular support, a 120 governor carried by the spindle and slidably on the support, and means for rotating the spindle.

SEBASTIAN G. BRINKMAN.
